UNITED STATES PATENT OFFICE.

MAURICE F. FITZGERALD, OF WINSTED, CONNECTICUT, ASSIGNOR TO THE FITZGERALD MFG. COMPANY, OF TORRINGTON AND WINSTED, CONNECTICUT, A CORPORATION OF CONNECTICUT.

DESIGN FOR A FLATIRON HANDLE STRAP.

Application filed November 10, 1926. Serial No. 19,667. Term of patent 14 years.

To all whom it may concern:

Be it known that I, MAURICE F. FITZGERALD, a citizen of the United States, residing at Winsted, in the county of Litchfield, State of Connecticut, have invented a new, original, and ornamental Design for Flatiron Handle Straps, of which the following is a specification, reference being had to the accompanying drawing, forming a part thereof.

Fig. 2 is an enlarged sectional view of the same.

I claim:

The ornamental design for a flatiron handle strap, substantially as shown.

In testimony whereof, I affix my signature.

MAURICE F. FITZGERALD.
